UNITED STATES PATENT OFFICE.

OSCAR C. MACK, OF ST. LOUIS, MISSOURI.

MATERIAL TESTER.

Application filed November 14, 1922. Serial No. 600,977.

To all whom it may concern:

Be it known that I, OSCAR C. MACK, a citizen of the United States, residing at St. Louis, in the State of Missouri, have invented a new and useful Improvement in Material Testers, of which the following is a specification.

The present invention relates to material testers and has to do particularly with means for rapidly determining the presence or absence of cotton and other vegetable fibers in woolen and silk goods.

Primarily, the invention has for its object efficacious treatment of a suspected material to determine admixture therein of vegetable fibers. Secondarily, the invention has for its object the conduct of a testing process in a rapid and efficient manner and with the destruction or damage of but a negligible quantity of material. Additionally, an object of the invention is to provide an economical type of apparatus for conducting tests such as hereinbefore suggested.

These and such other objects as may hereinafter appear are obtained by the novel constructions, combinations and arrangements hereinafter described.

A single sheet of drawings accompanies and is made a part of this specification, and in said drawings:

Fig. 1 is a vertical section of my invention showing material under test therein; and

Fig. 2 is an elevation of the several parts thereof in disassembled relation.

Like reference characters are used to designate similar parts in the figures in the drawing and in the specification which follows.

The test which I prefer to employ is a solubility test, hence I provide means for bringing a solvent into intimate and unobstructed contact with a fabric to be tested. While in the description that follows and in the drawing I refer to vessels of round or cylindrical configuration, these vessels could equally well be rectangular, hexagonal, octagonal, or other conventional shape.

Referring to Fig. 1, it will be noted that I provide a receiving vessel 10, of suitable size and depth, generally cylindrical in form and having a flat apertured cover or top. Into and about the aperture in the cover or top is secured a funnel-like or flaring neck 11 which is additionally secured to the vessel 10 by a handle 12, soldered or otherwise

suitably fastened to both of said members 10 and 11.

A funnel-like member 13 comprising two connected sections of varying coniform configuration is also provided. The smaller of such sections is adapted to be freely inserted into and within neck 11. A plurality of wedge collar rings 14, funnel-like members of the same internal diameter but of a varying material thickness, are provided, any one of said collars or rings being adapted to engage the lower rim or extremity of funnel 13 and be secured thereupon by frictional engagement therewith. A tapering or oblique interior in said collars or rings aids in the procurement of a snug interfit between said funnel 13 and each of said rings, as used, and also prevents the collar slipping beyond the proper limit upon the funnel.

Each of the collars 14 should be of spun brass or steel while the receiver 10 and the funnel 13 may be of light tinned material. Collars 14, used one at a time as indicated, are selected in accordance with the thickness of the material to be tested,—the thinner the material the thicker the collar. No collar 14 is too large, however, for free insertion into the neck 11 when seated upon funnel 13.

In order that a test shall be made, I first cut off a small square 15 of the material to be treated. This I place, un-wrinkled, across the top of neck 11. Upon this I rest funnel 13 to which is frictionally attached wedge-collar 14 of proper weight and diameter. The collar 14 causes the fabric 15 to be drawn securely and tightly across the top of neck 11 and insures an even distribution of test liquid therethrough. I am now ready to pour a solvent or test liquid into funnel 13. Having prepared the solvent which I elect to use, I pour a layer of about two inches thereof upon the material 15, which is of course visible from the top of funnel 13.

Cloth is composed of warp yarns and woof yarns. The warp yarns include the threads running with the material its length, while the woof yarns compose the filler or cross section. The test liquid, after being poured upon the fabric 15, will slowly filter therethrough, and in this movement will dissolve out all woolen and silken threads in the yarns. Cotton and other vegetable materials, being insoluble therein, are not

disturbed by the passage of the test liquid.

There can be little or no escape of the test solvent beyond the outer diameter of the wedge collar 14, for said collar, by its weight resting upon the tested material, arrests capillary absorption of the solvent beyond the boundary indicated, confining the test to a limited area with the resultant saving of time and solvent.

10 The constituents of the material 15 will determine the character of the action of the solvent as it proceeds to filter therethrough. If the material 15 is all wool, all silk, or a mixture of silk and wool, a round 15 or substantially round hole will be dissolved out of or "eaten" into the material. But if either warp yarn, or woof yarn, or both, contain cotton or other vegetable fiber, such vegetable fibers will not be dissolved and a 20 series of connected threads will extend across the tested circle otherwise "eaten" away by the solvent. Such threads and their direction will stand out predominantly, being made particularly so by the dissolution of 25 the previously contiguous and intertwined woolen or silk threads. The rapidity with which the "spurious" cotton fibers become visible, and the clearness with which they are visualized allow the test to be properly 30 designated a "visible" test. The presence

of the smallest quantity of cotton fiber is almost instantly apparent.

Where the material tested is all cotton, the test liquid here described will have no effect upon it other than to discolor the 35 material, as cotton fibers are insoluble in the test solution described.

For the purposes of rapid test, I find that a solution of freshly prepared flaked caustic soda (76% strength) in the proportion 40 of one ounce of soda to one pint of boiling water gives highly efficient and enlightening results, and for that reason such solution is to be recommended, although it is manifest that my apparatus may be used 45 with equal facility with any other solvent.

I claim:

In a testing apparatus for cloth, connecting vessels having conical sections adapted to telescope one within the other, and a 50 plurality of rings of uniform internal diameter and of varying thicknesses of material adapted to be secured to the conical section of one vessel prior to its insertion into the second vessel, the cloth to be tested 55 being disposed upon the conical section of the second vessel and determining the thickness of the ring to be selected.

OSCAR C. MACK.
